POINT ILLUMINATING AND MAGNIFYING
ATTACHMENT FOR LOOPING MACHINESShepard Schwartz, Nashville, Tenn., assignor to
May Hosiery Mills, Davidson County, Tenn.

Application September 18, 1946, Serial No. 697,703

6 Claims. (Cl. 112—25)

1

This invention relates to improvements in looping machines and particularly to an improved means for providing proper illumination and magnification of the points or needles of such a machine during the work applying operation.

In the manufacture of hosiery there is an intermediate stage at which the hosiery is complete except that the toe portion of each stocking is open. This opening is closed by an operation using a circular or dial type looping machine. In operating such a machine, the loops along the terminal edges at opposite sides of the opening in the stocking toe are superimposed and inserted by hand over the radially projecting needles or points carried by the dial portion of the looping machine. This operation is accomplished while the machine is operating and the points are moved past the operator. After all of the loops are properly placed on the dial points, the points are carried into the sewing mechanism of the machine where the loops are secured together to complete the stocking. The operation of placing the loops on the dial points is commonly referred to in the art as the "running on" operation and is a very tedious and exacting operation because of the small size and close arrangement of the fabric loops and the correspondingly fine pointed closely spaced dial points or needles. Because of the fineness of the work it is rather common under ordinary conditions for the operator to occasionally miss applying one or more loops in the proper manner to the dial points which results in an imperfect seam by reason of which the finished stocking may have to be rejected or placed in a subordinate price group. The operation also results in considerable eye strain and nervous fatigue on the part of the operator so that the efficiency of the operators on this type of machine is difficult to maintain at a reasonably high level.

It is conceived that adequate local illumination of the dial points and a magnification of the points and loops during the running on operation would have a very beneficial effect not only in eliminating missed or dropped loops but also in relieving the strain and fatigue on the operator thereby resulting in a much higher production of stockings having perfect seams.

Lenses and lens supporting devices for magnifying the loops and dial points have been previously proposed but such previously proposed arrangements have been subject to material defects and objection and have not met with a high degree of commercial success.

One of the defects of the previously proposed

2

devices is that they have failed to properly combine the illumination and magnifying means in a manner to provide the most suitable conditions for observing the points and loops during the running on operation. With previously proposed devices it has also been necessary for the operator to manually adjust the magnifying lens and move it by hand to keep it properly focused on the point at which the work is being applied. As the operator's hands are fully occupied with running the stocking loops on to the dial points, it is practically impossible to manually move the lens at the same time. This results in the condition in which the lens is frequently not properly positioned to focus on the point at which the work is being applied. The lens may thus become more of a hindrance than a help to the operator, particularly if the condition causes the operator to assume tense and strained positions in the attempt to compensate for the improper lens position and may at times cause additional eye strain because of the out of focus condition.

It is therefore among the objects of the present invention to provide visual aid means for a looping machine in the form of a magnifying lens having a support so constructed and arranged that the lens can be adjusted to the proper position without the necessity of removing the operator's hands from the work.

It is also an object to provide visual means for a looping machine in which a magnifying lens and a source of illumination are properly combined to provide the optimum condition for visibility in applying work to the machine.

A still further object resides in the provision of improved visual aid means for a looping machine which may be applied to an existing machine without requiring modification or rearrangement of any of the machine parts.

Another object resides in the provision of an improved visual aid means for a looping machine which is simple and economical in construction and may be easily applied to existing machines without incurring any excessive costs and which, while providing material assistance in improving the visibility of the work, will not cause inconvenience to the operator in other ways.

Other objects and advantages will become apparent as the description proceeds in connection with the accompanying drawing in which like reference numerals are used to designate similar parts throughout.

In the drawings, the single figure is a diagrammatical elevational view of a portion of a looping machine showing the application of the improved

visual aid means thereto, the visual aid means being shown partly in section to better illustrate the construction thereof.

With continued reference to the drawing, a looping machine of conventional construction is generally indicated at 10, portions thereof such as the loop sewing mechanism being omitted in order to simplify the drawing.

In the machine illustrated, a base portion 12 is supported by suitable means such as the cantilever arm 14 and includes suitable mechanism by means of which an operative drive is transmitted from a drive element, such as the shaft 16, to the rotatable dial 18. The dial carries a circular series of points or needles 20 to which the loops edging the seam to be formed are applied.

A stud 22 extends upwardly from the machine substantially coaxially with the dial 18 and is fixed relative to the support 14.

An anti-friction bearing, such as the ball bearing generally indicated at 24, is secured to the upper end portion of stud 22. In the arrangement illustrated, the inner race 26 of the bearing is forced upon the end of the stud and against a clamp collar 28 with a press fit which provides a sufficiently rigid connection between the inner race and the stud. A disc 30 has a cylindrical flange portion 32 into which the outer race 34 of the bearing is forced with a press fit to provide a rigid connection between the outer race and the disc. Thus by means of the antifriction bearing 24 the disc is rotatably supported upon the upper end of stud 32. If desired the disc may have a peripheral reinforcing bead 36.

An arm 38 extends across the top of the disc and is secured thereto by suitable means such as bolts, one of which is indicated at 40, and may have an end portion bent over the bead 36 if desired. This arm 38 may have attached thereto adjacent the edge of the disc, the bracket portion 42 of a lamp guard 44. The guard 44 carries a bulb 46 positioned to direct its light on to the dial points 20 at the location at which the work is applied to the points. Electrical current may be supplied to the bulb through conventional wires 48.

Attached to the arm 38 or to the guard 44, as may be convenient, is a lens rim 50 in which is supported a magnifying lens 52. This lens should have at least a limited freedom of universal adjustment relative to its support and a universal connection providing such freedom of movement is indicated at 54 operatively connected between the lens guard 44 and the lens rim 50.

A substantially vertical standard 56 is attached to the arm 38 or formed integrally therewith and at its lower end carries a roller 58 which rides on the upper surface of dial 18.

Friction in the mounting of the roller 58 tends to swing the disc 30 in the direction of rotation of the dial thus tending to carry the bulb 46 and lens 52 along with the dial as the work is applied.

A support arm 60 is secured to the stud 22 below the bearing 24 and at its outer end carries a hinged bracket 62 carrying a bearing 64 in which a shaft 66 is journaled.

At its inner end the shaft 66 has a friction roller 68 secured thereon and at its outer end a drive pulley 70. The drive pulley is operatively connected by suitable means, such as the belt 72, with an element of the machine drive, as diagrammatically indicated by the pulley 74 on shaft 16, so that shaft 66 is rotated whenever the machine is in operation.

The hinged bracket 62 has a hinge joint 76 about which the shaft 66 may oscillate under control of the foot pedal 78. In the arrangement illustrated the shaft is urged by suitable resilient means, such as the spring 80, to swing about the hinge joint 76 to a position in which the roller 68 is out of contact with the under surface of the disc 30. A lever arm 82 is connected at one end to the bracket 62 above the hinge joint 76 and at its opposite end through the intermediacy of a suitable tension member 84 with the foot pedal 78.

With this arrangement when the foot pedal 78 is depressed, the pulley 68 will be brought into frictional engagement with the under surface of disc 30 and when the foot pedal is released the spring 80 will move the roller away from the disc.

When the disc driving roller 68 is out of contact with the disc 30 dial contacting roller 58 will cause the disc to rotate in the same direction as the dial.

This will swing the arm 38 carrying the magnifying lens and lamp in the direction of dial rotation to follow the work applied to the dial points. Depression of the pedal 78, however, will cause the disc 30 to be driven in the opposite direction by the disc driving roller 68 causing the lamp and lens to swing in the direction opposite to dial rotation.

By properly controlling the foot pedal 78 the operator can cause the lamp and magnifying lens on arm 38 to assume any desired position along the arc of the dial where the work is being applied to the dial points. The universal mounting of the magnifying lens permits correct focusing of the lens on the dial points and by following up the location of the point to which the loops are being applied to the points the lens can be accurately focused on the work at all times. When the running on operation is complete the lens may be swung back and forth across the arc to inspect the work for any missed loops which can then be applied to avoid the formation of an imperfect seam.

The light bulb 46 and guard 44 are so constructed and are so arranged with respect to the magnifying lens 52 that the operator's eyes are shielded from direct light but a sufficiently strong light is reflected from the work and the dial points through the lens to provide excellent visibility of the work as it is being applied to the dial points.

It will be obvious to those skilled in the art that various changes may be made in the invention without departing from the spirit and scope thereof and therefore the invention is not limited by that which is shown in the drawings and described in the specification but only as indicated in the appended claims.

What is claimed is:

1. A visual aid attachment for a looping machine having a rotatable dial and a relatively fixed stud at the center of said dial, said attachment comprising a disc mounted on said stud for free rotation relative thereto; an arm extending outwardly from said disc; a magnifying lens carried at the outer end of said arm in position to magnify the dial points at the location at which work is applied thereto; a dial contacting roller carried by said arm to move said lens with said dial to follow the application of work to said points; and means for swinging said lens in the opposite direction comprising an arm on said stud, a hinged bracket on said arm, a shaft jour-

nalled in said bracket, a roller on one end of said shaft frictionally engageable with said disc, a drive pulley on said shaft operatively connected with the driving mechanism of said machine, holding means associated with said shaft carried roller to normally hold said roller out of contact with said disc, and operator controlled means operative to bring said friction roller into driving contact with said disc.

2. A visual aid attachment for a looping machine having a rotatable dial and a relatively fixed stud at the center of said dial, said attachment comprising a disc mounted on said stud for free rotation relative thereto; an arm extending outwardly from said disc; a magnifying lens and a shielded light source carried at the outer end of said arm; a dial contacting roller carried by said arm to move said lens and light source with said dial to follow the application of work to said dial points; and means for moving said lens and light source in the opposite direction comprising a roller normally out of engagement but frictionally engageable with said disc, means for driving said normally disengaged disc roller; and operator controlled means for bringing said roller into frictional engagement with said disc.

3. A visual aid attachment for a looping machine having a rotatable dial and a relatively fixed stud at the center of said dial, said attachment comprising a disc mounted on said stud for free rotation relative thereto; an arm extending outwardly from said disc; a magnifying lens carried at the outer end of said arm in position to magnify the dial points in the location that the work is applied thereto; a dial contacting roller carried by said arm to move said lens with said dial to follow the application of work to said dial points; and means controllable by the foot of the operator drivingly associated with said disc to move said lens in the opposite direction.

4. A visual aid attachment for a looping ma-

chine having a rotatable dial and a relatively fixed stud at the center of said dial, said attachment comprising a disc mounted on said stud for free rotation relative thereto; an arm extending outwardly from said disc; a magnifying lens carried at the outer end of said arm in position to magnify the dial points at the location to which work is applied thereto; means associated with said disc to move said lens with said dial to follow the application of work to said points; and means also associated with said disc and including a foot pedal, operative to move said lens in the opposite direction at the will of the operator.

5. A visual aid attachment for a looping machine as defined in claim 4 wherein an anti-friction bearing is interposed between said disc and said stud and a collar disposed on said stud to facilitate positioning said bearing thereon.

6. A visual aid attachment for a looping machine having a rotatable dial and a relatively fixed stud at the center of said dial, said attachment comprising rotatable means associated with said stud and supporting an arm extending outwardly therefrom; a magnifying lens carried by said arm and positioned to magnify the dial points in the location that the work is applied thereto; means carried by said arm to move said lens with said dial to follow the application of work to said dial points; and operator controlled means associated with said first mentioned means operative to move said lens in the opposite direction.
